CLAIM

The ornamental design for a portable water pump, as shown and described.

DESCRIPTION

FIG. 1 is a right side elevational view of a portable water pump showing my new design, the left side being a mirror image;

FIG. 2 is a front elevational view thereof;

FIG. 3 is a rear elevational view thereof;

FIG. 4 is a top plan view thereof; and,

FIG. 5 is a front, rear and right side perspective view thereof, the cable element being shown broken-away in the views to indicate indeterminate length.

FIG 1

FIG 4
